(57) **ABSTRACT**

A system for protecting articles, especially displayed goods, from theft is typically configured to produce information about the article when a person is detected approaching the article or the article is moved but not taken. The system typically includes an alarm which may be sounded if the article is moved too far from the display position or under other conditions.

SYSTEM AND DEVICE FOR PROTECTING
ARTICLESCROSS REFERENCE TO RELATED
APPLICATIONS

This application, is a continuation of U.S. patent application Ser. No. 13/537,623, filed Jun. 29, 2012; which is a continuation application of U.S. patent application Ser. No. 12/064,026, filed Sep. 23, 2008; which is a national stage application which claims benefit under 35 U.S.C. 371 of International Application No. PCT/EP2006/008083, filed Aug. 16, 2006; which in turn takes its priority from German Application No. 10 2005 038 811.6, filed Aug. 17, 2005, and all of whose entire disclosures are incorporated herein by reference.

BACKGROUND OF THE INVENTION

This invention relates to a method for the securing of objects, in particular of items of merchandise put on display, wherein an alarm is produced when the object is stolen. Furthermore, the present invention relates to an apparatus for implementing the method, wherein for the protection of objects against theft, including in particular items of merchandise put on display, provision is made for a sensor that is adapted to be affixed to the object to be secured and is connected to a checking and alarm device for activating an alarm on response of the sensor.

The surveillance of freely presented objects to protect them against theft by means of a sensor that is connected to a checking and alarm device via a current line is known in the art. When the line or the antitheft installation is manipulated or the sensor is removed, the checking and alarm device sets off an audible and visual alarm.

Moreover, sales-promoting systems are known using, for example, end-less-loop audiovisual advertising. They suffer however from the disadvantage of not allowing perfectly timed advertising relating to a particular product and geared to the specific information needs, accordingly resulting in high coverage losses.

BRIEF DESCRIPTION OF THE DRAWINGS

The present invention will become more fully understood from the detailed description and the accompanying drawings, wherein:

FIG. 1 is an apparatus for protection against theft as well as for the automatic output of product information; and

FIG. 2 is an apparatus similar to the one of FIG. 1 but including a distance sensor.

DESCRIPTION OF THE PREFERRED
EMBODIMENT

The following description of the preferred embodiment(s) is merely exemplary in nature and is in no way intended to limit the invention, its application, or uses.

It is an object of the present invention to provide a method and an apparatus of the type initially referred to, which enables specific, product-related advertising while at the same time providing for reliable surveillance of the displayed object and requiring a comparatively small outlay particularly in equipment and installation.

To accomplish this object, with regard to the method of the invention it is proposed that, apart from an alarm being set off when the object is stolen, a logging function is performed

2

when a person approaches the object or removes the object without taking it away, and at least one action is started with the logging, which action includes at least a product information about the object being displayed.

With regard to the apparatus it is proposed that it include a logging device performing a logging function when a person approaches the object on display or removes the object without taking it away, that to this effect a sensor be provided that responds when a person approaches or removes the object and is in controlling communication with the checking and alarm device, and that the checking and alarm device be connected to a product information device for presenting the displayed object.

By reason of the logging using an additional logging sensor operable on a person's approaching or removing the object connected to the checking and alarm device already provided as antitheft device, it is possible to attract a prospective customer's/viewer's interest in simple manner by presenting, for example, the function of the exhibit. Considering that essential components of the antitheft device, which generally is already provided, can be shared, a simple and economical system expansion is possible by adding the product information as a supplementary function.

Preferably, the product information about the object on display is by audiovisual devices, since this allows a comprehensive information in a particularly intensive, fast and effective way. The audiovisual product information may be output preferably by means of a product information device including a video data base with an in particular digital player and a connected visual display unit for visual display and, as the case may be, a loudspeaker and/or headset for listening.

Typically, a free presentation includes a plurality of objects. When, as a further action, events are counted and/or date and/or time of the day are saved, the detections may be stored with date and time of the day for later reference in statistical analyses in order to obtain information about the attractiveness of the object put on display. For this purpose, the checking and alarm device includes a storage memory for storing the event count and/or date and/or time of the event.

In the absence of a current event being detected, no product-related promotion will be shown, instead general advertising may be shown in the mean-time. This may include manufacturer advertising of the displayed object or market advertising. These advertising periods as well as the aforementioned statistical data obtained may be evaluated and/or sold to the manufacturers, for example.

Particularly electronic products in the fields of information technology and audio/video equipment are as a rule freely presented in substantial quantities. When a theft alarm is set off, it is therefore difficult to be able to locate the site of the theft promptly.

Therefore, it may be useful when, in the case of a theft, an audible alarm is set off and an at least visual alarm concerning the object to be secured is produced by the device provided for audiovisual product information.

In the case of a theft alarm it is thus possible to output on the visual display unit associated with the stolen object a product-related alarm notification, thereby enabling the site of the theft to be located promptly.

Using the same infrastructure, it is hence possible to place the freely presented objects under surveillance, allowing a fast, product-related visualization of the alarm on the one hand and promotion of the objects on the other hand, which results in significant cost reductions in investment and the obtainment/sale of statistical data.

It is also worth mentioning that the logging sensor is also capable of tripping further promotional actions including, for

example, actions that also address the other sense organs, such as scents, wind and the like.

The sensor of the logging device may be a motion sensor. It operates to start the product information when a prospective buyer approaches or stands in front of the product on display. No additional action is required in this case.

However, the possibility also exists for the sensor of the logging device to be a removal sensor. In this event the product information is not started until the prospective buyer takes the product in his hand, showing an apparent interest in it. False activations as may be caused by a passing customer are thereby avoided.

In either event, the product information is activated when the prospective buyer is within a predetermined range in the region of the displayed product.

The sensor may also be used as a special proximity sensor for distance measurement. This distance sensor is arranged in the proximity of the displayed object to be secured and detects the distance between it and an object to be secured or a person approaching it.

Among other things, the measured distance may be evaluated for a signaling function, where appropriate, with activation of a product-related information and/or an early warning and a theft warning. When the product is removed and kept within a distance of, for example, 2 m, a logging signal may be issued, for example, by activation of an orange LED light in order to indicate to the user that his action is recorded. Should he move away from the distance sensor together with the product by a distance of more than two meters, for example, this would be interpreted as theft, and an alarm would be triggered.

When a person approaches the displayed object, the product information is started, where appropriate together with the early warning. The proximity sensor may also be configured such as to respond when the displayed object is touched. Accordingly, an action may be released on approaching, removing or touching the displayed object.

The sensor of the logging device may also be a switch, in particular a mechanical or capacitive or inductive or optoelectronic or magnetic switch.

Particularly advantageously, the sensor of the logging device is part of the antipilferage sensor arrangement, because this enables multiple use to be made of existing equipment.

In a preferred embodiment, the antipilferage sensor arrangement may include a sensor affixed to the object to be secured, which sensor is connected to the checking and alarm device through a cable wound on a cable retractor, with the sensor of the logging device being configured to detect when the wound-up cable is being pulled off the cable retractor. The cable retractor provides for a "tidy" presentation.

The sensor may be configured as a magnetic switch comprising a reed contact mounted on the enclosure of the cable retractor and a magnet fitted to the pull-out type cable.

In this arrangement it is suitable for the magnet fitted to the cable to be constructed as a cable stop resting against an abutment with the cable in roughly wound-up condition.

Such a sensor arrangement affords, inter alia, the advantage of being retrofittable with ease.

While the apparatus of the invention and the related method are primarily concerned with the securing of items of merchandise, they may also find utility in exhibitions, galleries, for example, to provide the viewer with explanations/information, and, on the other hand, in the securing of the exhibits, such as paintings, against theft. The theft detection sensor may be affixed preferably to the frame or the like,

while the logging sensor is preferably a motion sensor that, on recording a viewer's presence, starts the output of information.

The present invention with its essential details will be described in more detail in the following with reference to two embodiments. In the drawings showing in a somewhat schematic view.

As used throughout, ranges are used as shorthand for describing each and every value that is within the range. Any 10 value within the range can be selected as the terminus of the range. In addition, all references cited herein are hereby incorporated by reference in their entireties. In the event of a conflict in a definition in the present disclosure and that of a cited reference, the present disclosure controls.

15 An apparatus 1 shown in FIG. 1 serves the dual purpose of protecting items of merchandise put on display or objects 2 against theft and performing a logging function when a person approaches the object 2 or removes the object without taking it away. When a logging function is performed, at least 20 one action, namely a product information about the object on display, is started.

The objects 2, which include cell phones, for example, are freely accessible to the prospective buyer in one or several display shelves 6. Depending on the configuration of the 25 apparatus 1, up to 250 items may be subjected to surveillance and presented by audiovisual devices.

The apparatus 1 includes a theft detection sensor 3 that is affixed to the object 2 to be secured and is connected to a checking and alarm device 4 by means of a cable 5. When the 30 sensor 3 responds when removed from the object 2 or when the cable 5 is severed/manipulated, a theft alarm will be produced.

When a person approaches or removes the object 2 on display, this will be recorded by a logging device, the ensuing 35 action then being an audiovisual product information. In the embodiment shown, the logging device includes a removal sensor 7 which is in controlling communication with the checking and alarm device 4 provided as antitheft device via a cable 8, so that both functions require only one shared 40 checking and alarm device.

The cable 5 connected to the theft detection sensor 3 is wound on a cable retractor 9.

The removal sensor 7 is configured to detect when the wound up cable 5 is being unwound from the cable retractor 45 9.

In the embodiment shown the sensor 7 is constructed as a magnetic switch having a reed contact 11 fitted to the cable retractor enclosure 10 as well as a magnet 12 fitted to the pull-out type cable 5.

50 The reed contact is preferably embedded in plastic and may be mounted on or in the cable retractor enclosure 10. Aside from its function as a permanent magnet for switching the reed contact as soon as the magnet leaves its position of rest when the cable is pulled out, causing the magnetic field at the 55 reed contact to be interrupted, the magnet 12 has the added function of a cable stop for pull-relief of the cable 5 and the connected sensor 3 in the rest position. In this arrangement, the magnet 12 affixed to the cable 5 functions as a cable stop, resting in roughly wound-up condition of the cable 5 against 60 an abutment defined by the enclosure 10 in this embodiment.

It is particularly advantageous in this arrangement for the sensor 7 (event sensor) to be retrofittable easily, to be a low-cost and sturdy item and to require little space.

For presenting the objects 2 put on display, product information devices 13 are in controlling communication with the checking and alarm device 4. The product information device 65 13 contains a function block 14 with a video data base and a

digital player as well as a visual display unit 15. The dashed line indicates that plural, for example, ten, product information devices 13 may be connected to the checking and alarm device 4.

Depending on which removal sensor 7 was activated, the associated product information is retrieved from the video data base and shown on the visual display unit 15.

A product information device 13 may be assigned to single objects 2 or a plurality, particularly a group, of similar objects on display. How many objects 2 are allocated to a product information device 13 depends, *inter alia*, on the object size. For example, 25 exhibits 2 may share one product information device 13 with a video data base and a digital player as well as a visual display unit 15.

The modular design enables the apparatus 1 to be configured individually in conformity with the given conditions. Thus, an existing apparatus for theft detection is readily extendable and with relatively little effort to include one or plural product information devices 13 and one or plural removal sensors 7, providing a system enabling the output of specific product information. On the other hand, the product information device 13 or several such devices may also be used as standalone with one or several removal sensors 7.

FIG. 2 shows in a further embodiment an apparatus 1a in which a proximity sensor is constructed, as a distance sensor 7a.

In the embodiment shown, the distance sensor 7a includes an antenna 17 or similar detecting element which is connected to a receiver 16 preferably integrated into the checking and alarm device 4a. The antenna 17 is arranged behind the object 2 to be secured and/or also behind the display shelf 6.

The distance sensor 7a serves to detect the relative distance of a person and/or the object 2 to be secured and/or a sensor 3a affixed to the object 2 to be secured to the antenna 17 of the distance sensor 7a.

In combination with the distance sensor 7a, the checking and alarm device 4a may be configured and/or adjustable to produce a signal when the object 2 to be secured is approached, touched or moved within a predetermined removal distance, and to set off a theft alarm when this removal distance is exceeded.

In the embodiment, a sensor 3a is affixed to the object 2 to be secured, said sensor including a transmitter and at least digital/analog inputs in particular for microswitches or for a safety film for article surveillance as well as for battery monitoring of a supply battery. The distance sensor 7a responds also when a person approaches the antenna 17, whose operating range may be two meters, for example. It is able to detect whether a person approaches this antenna 17, which is assigned to a displayed object 2, and to what distance.

In addition, this distance sensor 7a also detects through the antenna 17 the distance between the product 2 equipped with the sensor 3a and the antenna 17. Hence it can be established whether the product was removed from the shelf 6 and how far away from its original location. For example, this enables a logging signal to be issued to inform the user that his action is recorded. In particular when the proximity sensor or distance sensor 7a responds, a product-related promotion and information function is started for the customer. When the object 2 is carried farther away from its original location, then a theft alarm may be set off.

Where appropriate, added provision may be made for tracking the removed object 2 within the premises, with corresponding signaling. During tracking the sensor 3a has a function comparable to a transponder chip (RFID) otherwise affixed to the product.

Furthermore, the distance sensor 7a may detect through the antenna 17 whether an approaching person is authorized to manipulate the apparatus. Such persons carry an electronic key 18 which transmits corresponding ID data to the antenna 17 and hence to the receiver 16 or the checking device 4a. Thus a wireless authorization check with in particular capacitive transmission takes place.

The possibility also exists for the distance sensor 7a to include several antennae 17 at one site subject to surveillance, which antennae are arranged such that, *inter alia*, also the direction in which the object 2 to be secured is removed is detectable. It is also possible to arrange several antennae at predetermined distances, spacing them, for example, at 5-meter distances within the market or similar premises, thus enabling the product to be tracked on the premises.

Several distance sensors 7a may be connected to the checking and alarm device 4a, whereby one receiver 16 may have connected to it several antennae 17, each assigned to one surveillance site.

It is noted that for proximity and/or contact sensing use may also be made of the conductivity of the skin and an electrostatic near-field wherein information transfer is possible via the skin and, on the other hand, the variation of an electric field by a human being is detectable.

In this arrangement, for example, a transmitter integrated into the electronic key 18 (FIG. 2) may be used for producing the electrostatic field and couple its signal into a persons skin, which also functions without direct skin contact. By modulating data onto the signal voltage spreading over the entire skin surface, information items may be transmitted as, for example, for identification purposes.

In practice, the following construction is possible:

On an active data transmission through the skin, small transmitters carried close to the human body produce an electric field through which coded information items, coupled directly or capacitively, can be transmitted to one or several receivers. In this way, the information transmitted may identify an object or a person.

However, such signals can be received only if objects equipped with transmitters are in close proximity to the human body. Switching operations can then be released promptly. However, this process may also be reversed. When these objects are removed, causing the transmission to be aborted, a prompt switching operation can equally take place.

It is also possible to detect the variation of an electric field by an approaching person or a person who is within the range of the electrostatic field, hence detecting passively the presence of a body as it comes closer and using this condition to trigger an action, for example, a product information.

In contrast to the active transmission of signals, the passive detection of a body approaching does not involve an identification function.

When, for example, a sensor 3a with a transmitter is affixed to the object 2 to be secured, it is possible to detect a theft of the object 2 taken by the thief, because the transmitter affixed to the object 2 couples its signal into the person's skin surface, producing an electrostatic field in the process. Through receivers which may be distributed to various locations in a market, this field can be received and evaluated, hence enabling the stolen object to be tracked.

Accordingly, when the proximity sensor 7 and/or the sensor 3 affixed to the object 2 to be secured is equipped with a transmitter, an electrostatic field can be generated which can be put to various uses. As described in the foregoing, the electrostatic field can be coupled into a person's skin surface and used, for example, for the transmission of data. On the

other hand, an evaluation of the variation of the electrostatic field by an approaching person can also be used for triggering an action.

While the invention has been described with respect to specific examples including presently preferred modes of carrying out the invention, those skilled in the art will appreciate that there are numerous variations and permutations of the above described systems and techniques. It is to be understood that other embodiments may be utilized and structural and functional modifications may be made without departing from the scope of the present invention. Thus, the spirit and scope of the invention should be construed broadly as set forth in the appended claims.

What is claimed is:

1. A system comprising:

a merchandise item protection apparatus comprising:

a theft detection sensor configured to be affixed to an item of merchandise, the theft detection sensor being further configured to generate a theft detection sensor response when the theft detection sensor is removed from the item of merchandise,

an antenna,

a checking and alarm device connected to the antenna, the checking and alarm device being configured to produce a theft alarm based on the theft detection sensor response,

a removal sensor, and

a cable connected to the theft detection sensor, the cable having a magnet attached thereto, where the removal sensor comprises a magnetic switch configured to be actuated in response to interruption of a magnetic field generated by the magnet attached to the cable; and

an electronic key including a transmitter configured to transmit data to the antenna,

wherein the checking and alarm device is further configured to receive the data via the antenna and perform a wireless authorization check of the electronic key.

2. The system of claim 1, wherein the theft detection sensor is connected to the cable, and wherein the theft detection sensor generates the theft detection sensor response when the cable is severed.

3. The system of claim 1, wherein the magnet is configured to operate as a cable stop for the cable by resting against an abutment when the cable is being refracted onto a cable retractor.

4. The system of claim 1, wherein the theft detection sensor includes a wireless transmitter.

5. The system of claim 4, the system further comprises a distance sensor that detects a distance that the item of merchandise has been moved using the wireless transmitter of the theft detection sensor.

6. The system of claim 5, wherein the system further comprises at least one additional antenna, wherein the checking and alarm device is configured to detect a direction in which the item of merchandise is moved based on signals received via the at least one additional antenna.

7. The system of claim 1, wherein the transmitter of the electronic key is configured to produce an electric field that couples to a person's skin when the electronic key is proximate the person's body.

8. The system of claim 7, wherein the transmitter capacitively couples with the person's skin.

9. The system of claim 7, wherein the transmitter of the electronic key is further configured to modulate data onto a signal voltage that generates the electric field.

10. The system of claim 1, wherein the theft detection sensor includes a theft detection sensor transmitter configured to generate a field that couples with a person's skin that is handling the item of merchandise.

11. An apparatus comprising:
a theft detection sensor configured to be affixed to an item of merchandise, the theft detection sensor being further configured to generate a theft detection sensor response when the theft detection sensor is removed from the item of merchandise;

an antenna;

a checking and alarm device connected to the antenna, the checking and alarm device being configured to: produce a theft alarm based on the theft detection sensor response,

receive data via the antenna from an electronic key, and perform an authorization check of the electronic key;

a removal sensor; and

a cable connected to the theft detection sensor, the cable having a magnet attached thereto, where the removal sensor comprises a magnetic switch configured to be actuated in response to interruption of a magnetic field generated by the magnet attached to the cable.

12. The apparatus of claim 11, wherein the theft detection sensor is connected to the cable, and wherein the theft detection sensor generates the theft detection sensor response when the cable is severed.

13. The apparatus of claim 11, further comprising a display surface, wherein the removal sensor is configured to generate a removal sensor response when the item of merchandise is removed from the display surface.

14. The apparatus of claim 11, wherein the removal sensor is configured to provide a removal sensor response that activates a presentation of associated product information retrieved from a video database and displayed on a visual display unit.

15. The apparatus of claim 11, wherein the theft detection sensor includes a wireless transmitter.

16. The apparatus of claim 11, wherein the antenna is configured to receive the data from the electronic key via an electric field that is coupled to a person's skin when a transmitter of the electronic key is proximate the person's body.

17. The apparatus of claim 16, wherein the antenna is further configured to receive the data from the electronic key that has been modulated onto a signal voltage that generates the electric field.

18. The apparatus of claim 11, wherein the theft detection sensor includes a theft detection sensor transmitter configured to generate a field that couples with a person's skin that is handling the item of merchandise.

19. An electronic key apparatus comprising:
a memory including data; and
a transmitter configured to transmit the data to an antenna of a merchandise item protection apparatus, wherein the merchandise protection apparatus includes a checking and alarm device configured to produce a theft alarm based on a theft detection sensor response provided by a theft detection sensor, and further configured to receive the data via an antenna connected to the checking and alarm device and perform a wireless authorization check of the electronic key, and wherein the transmitter of the electronic key capacitively couples with a person's skin and is configured to produce an electric field that couples to the person's skin when the electronic key is proximate the person's body.

20. The electronic key apparatus of claim 19, wherein the transmitter configured to transmit the data is further config-

ured to transmit the data to the antenna of the merchandise item protection apparatus, the theft detection sensor of the merchandise protection apparatus being connected to a cable, and the theft detection sensor being configured to generate the theft detection sensor response when the cable is severed. 5

21. The electronic key apparatus of claim **19**, wherein the transmitter is further configured to modulate data onto a signal voltage that generates the electric field.

22. The electronic key apparatus of claim **21**, wherein the modulated data is used for identification. 10

It is certified that error appears in the above-identified patent and that said Letters Patent is hereby corrected as shown below:

On the title page, under abstract “22 Claims, 2 Drawing Sheets” should read --23 Claims, 2 Drawing Sheets--.

In the Claims

Column 7

Line 44, please insert --1-- following “claim”.

Line 63, please delete “8. The system of claim 7, wherein the transmitter capacitively couples with the person’s skin.”.

Line 65, please delete “9” and insert in place thereof --8--.

Column 8

Line 1, please delete “10” and insert in place thereof --9--.

Line 5, please delete “11” and insert in place thereof --10--.

Line 24, please delete “12” and insert in place thereof --11--.

Line 24, please delete “11” and insert in place thereof --10--.

Line 28, please delete “13” and insert in place thereof --12--.

Line 28, please delete “11” and insert in place thereof --10--.

Line 32, please delete “14” and insert in place thereof --13--.

Line 32, please delete “11” and insert in place thereof --10--.

Line 37, please delete “15” and insert in place thereof --14--.

Line 37, please delete “11” and insert in place thereof --10--.

Line 39, please delete “16” and insert in place thereof --15--.

Line 39, please delete “11” and insert in place thereof --10--.

Line 43, please delete “17” and insert in place thereof --16--.

Line 43, please delete “16” and insert in place thereof --15--.

Line 47, please delete “18” and insert in place thereof --17--.

Line 47, please delete “11” and insert in place thereof --10--.

Line 51, please delete “19” and insert in place thereof --18--.

Line 66, please delete “20” and insert in place thereof --19--.

CERTIFICATE OF CORRECTION (continued)
U.S. Pat. No. 8,890,690 B2

Page 2 of 2

Line 66, please delete “19” and insert in place thereof --18--.

Column 9

Line 6, please delete “21” and insert in place thereof --20--.

Line 6, please delete “19” and insert in place thereof --18--.

Line 9, please delete “22” and insert in place thereof --21--.

Line 9, please delete “21” and insert in place thereof --20--.

Line 11, please insert --22. A system, comprising:

a merchandise item protection apparatus, comprising:

a theft detection sensor including a wireless transmitter, wherein the theft detection sensor is configured to be affixed to an item of merchandise and the theft detection sensor is further configured to generate a theft detection sensor response when the theft detection sensor is removed from the item of merchandise, an antenna, and

a checking and alarm device connected to the antenna, the checking and alarm device being configured to produce a theft alarm based on the theft detection sensor response;

a distance sensor that detects a distance that the item of merchandise has been moved using the wireless transmitter of the theft detection sensor; and

an electronic key including a transmitter configured to transmit data to the antenna;

wherein the checking and alarm device is further configured to receive the data via the antenna and perform a wireless authorization check of the electronic key.

23. The system of claim 22, wherein the transmitter of the electronic key is configured to produce an electric field that couples to a person’s skin when the electronic key is proximate the person’s body.--.
